CHUCKING MACHINE

Filed Oct. 22, 1935

4 Sheets-Sheet 1

Fig. 1.

Detailed description of the diagram: The diagram is a technical cross-sectional view of a mechanical assembly. At the top, a flywheel (113) is connected to a motor (114) via a belt (106). A pressure gauge (107) is attached to a valve assembly (108). Below the flywheel, a pump housing (115) contains a pump shaft (116) with a gear (117). A valve (118) is connected to the pump shaft. A large rectangular component (119) is positioned below the pump, with a valve (120) and a pipe (121) leading to it. The central part of the diagram shows a complex arrangement of gears (122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 698, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 798, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 898, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1198, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1298, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1398, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1498, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1598, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1698, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1798, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, CHUCKING MACHINE

Donald H. Montgomery, West Hartford, and Robert C. Nelson, Kensington, Conn., assignors, by mesne assignments, to The New Britain Machine Company, New Britain, Conn., a corporation of Connecticut

Application October 22, 1935, Serial No. 46,084

27 Claims. (Cl. 29—38)

Our invention relates to a chucking machine and more particularly to hydraulic mechanism for operating parts of such a machine.

The invention will be described as embodied in a multiple spindle chucking machine of the type described in Gridley et al. application, Serial No. 551,136, filed July 16, 1931, to which reference is made for a fuller disclosure of such a machine. In said Gridley et al. application, there is disclosed a four spindle work rotating type of chucking machine. Each chuck is fluid pressure actuated and each spindle is clutched to and unclutched from its drive gear or power train by fluid pressure actuated means, and the chucking and clutching functions are controlled by a single handle. The spindles are mounted in an indexible spindle carrier and as each spindle is indexed to the loading station it is declutched from the power train and the chuck 10 opened, after which a new work piece is inserted, the chuck closed, and the spindle again clutched to the power train prior to reaching the first work station. Our present invention, as stated, will be described as embodied in a machine of the said Gridley et al. type, but it is to be understood that the principles of our invention are of broader application and may be embodied in machines of other types and in machines having one or more spindles.

It is an object of our invention to provide fluid pressure actuated chucking and clutching means so interrelated as to reduce the dangers to an operator and to machine parts to a minimum.

It is a more specific object to provide fluid pressure actuated clutch and chuck mechanism so controlled as to prevent work pieces from being unchucked until the spindle has been unclutched from the drive train.

A further object of the invention is to provide means for automatically stopping the machine or preventing indexing of the carrier should the work piece fail to be properly chucked and the spindle clutched to the drive train.

It is another object to provide fluid pressure actuated chuck and clutch mechanism arranged for automatic declutching of the spindle from the drive train and manual unchucking in the loading station.

It is a further object to provide fluid pressure actuated chuck and clutch mechanism controlled by a single handle together with delayed action means to cause one function to be performed in advance of the other.

It is another object to provide independently regulable pressure means for controlling the

clutch mechanism between the spindle and the power train and for controlling the chucking mechanism and for holding the work chucked in work station or stations.

It is another object to provide fluid pressure actuated chucking mechanism, together with safety means, for stopping the machine in the case of attainment of an abnormal pressure condition in the chucking means.

Other objects and various features of novelty and invention will either become apparent to those skilled in the art or will be hereinafter set forth.

Briefly stated, in a preferred form of the invention, we may employ an indexible spindle carrier carrying a plurality of rotatable spindles having chucks. The chucks are actuated by fluid pressure and each spindle in loading station is clutched to and declutched from its drive gear or power train by fluid pressure actuated means.

The chucking and clutching functions are under control of a single member, such as a hand-operated lever, when hand feeding is resorted to. The interrelation of the chucking and clutching functions is such that danger to an operator by reason of the starting of the spindle rotation before or immediately after the work piece is chucked up is reduced to a minimum. We preferably provide means for automatically declutching each spindle from the power train in loading station and manual means for unchucking the work piece, together with the same manual means for chucking up a new work piece, and preferably also for clutching the spindle to the power train.

In case of a failure of chucking or clutching functions to be properly accomplished, we provide means for automatically stopping the machine or preventing indexing of the spindle carrier. Pressure fluid for holding the chucks in work stations closed may be and preferably is different from the pressure of the fluid employed for chucking up the work piece in the loading station. Furthermore, the pressure of the fluid for actuating the clutch mechanism may be and preferably is different from either of the other pressures. All of these pressures are regulable at will to meet varying conditions. We also provide means for stopping the machine in case of an abnormal pressure condition, for example, a dangerous drop in pressure which might endanger the hold of the chuck on the work piece, with consequent serious danger of damage to tools and other parts.

In the drawings which show, for illustrative

55

purposes only, a preferred form of the invention as embodied in a machine of the type disclosed in said Gridley et al. application—

Fig. 1 is a more or less diagrammatic view of 5 a machine of the type indicated, equipped with our improved fluid pressure chuck and clutch mechanism and associated parts;

Fig. 2 is a fragmentary end view of a machine as disclosed in said Gridley et al. application and 10 illustrating features of our improved fluid pressure actuated chucking and clutching mechanism;

Figs. 2a and 2b are sectional views taken respectively in the plane of lines 2a—2a and 2b—2b 15 of Fig. 1;

Fig. 3 is a sectional view taken substantially in the plane of the line 3—3 of Fig. 2;

Fig. 4 is a sectional view taken substantially in the plane of the line 4—4 of Fig. 2 and illustrates parts of the clutch control mechanism; 20

Fig. 5 is a sectional view taken substantially in the plane of the line 5—5 of Fig. 2 and illustrates the clutch actuating piston and associated parts;

Fig. 6 is a fragmentary sectional view taken substantially in the plane of the line 6—6 of Fig. 3 and 25 illustrates parts of a safety device;

Fig. 7 is a view similar to Fig. 6 but illustrating parts in different positions.

In said drawings and as is more fully set forth in said Gridley et al. application, the machine embodies a plurality of rotatable spindles, such as 5, all mounted for rotation in an indexible 30 spindle carrier. Each indexing movement brings one spindle from the last work station to the loading station. Each spindle is provided with a movable clutch member 6 keyed thereto and engageable with a coacting clutch member 7 constantly driven by the gear 8 of the power 35 train. The clutch illustrated is of the simple toothed type but it is to be understood that in practice the clutch mechanism may be substantially as disclosed in said Gridley et al. application, namely, one involving a friction pick up and 40 a positive drive.

Each spindle carries work holding or chucking means 9 for gripping work pieces 10. Each chuck is actuated by a draw rod carrying a piston 11 in a cylinder 12. Pressure on the tail 45 end of the piston 11 in the form shown serves to close the chuck on the work and pressure on the head end of the piston 11 serves to open the chuck. Pressure fluid under control of means to be later described is introduced into the cylinder 12 to actuate the piston 11 and consequently the chuck 9. Suffice it to say here that the chuck is actuated in loading station preferably by pressure fluid from an accumulator while the pistons of all of the cylinders in work station are maintained in the chucked up position by pressure fluid directly from the pump which serves to charge the accumulator. The chucking up pressure and the holding pressure may 50 be, and in most cases will be, different and regulable.

The clutch member 6 is also actuated by pressure fluid preferably from the accumulator and the pressure acting on the clutch operating mechanism may be different from the pressure employed for actuating the chuck mechanism.

As shown particularly in Fig. 1, a pump 13, which preferably operates continuously, draws fluid such as oil from the sump through a suction pipe 14 and delivers same through the de-

livery pipe 15 to a main regulating valve designated generally 16 and into a bore 17 therein. 5

18 is what may be termed a pressure retaining valve backed up and urged toward the left by means of a spring 19 adjustable as to stress by means of a screw 20. When the valve 18 is closed by the spring 19, the pump must build up a pressure in the bore 17 sufficient to overcome the stress of the spring 19 in its adjusted condition.

When such pressure is built up, the valve 18 is moved toward the right and fluid then passes the valve and flows into the air bell or 10 accumulator 21.

The accumulator 21, it will be understood, cannot be charged until the pressure in the bore 17 below the valve 18 has been built up to a predetermined amount determined by the adjustment of the spring 19 and such predetermined pressure is maintained in passage 17 while the accumulator is being charged.

If for any reason an excessive pressure in the passage 17 should be built up the pressure is relieved by the pressure relief valve 22 set by its spring to open at a predetermined pressure equal to or greater than the normal pressure desired in bore 17.

When the accumulator 21 has been charged by compressing the air in the upper part thereof to the desired degree, the pressure of the accumulator 21 will serve to move the accumulator 20

regulating valve 23 toward the right and against the spring 24 adjustable as to stress by means of a screw 25.

When the valve 23 is moved to the right to an open position, excess fluid passes into a pipe 26 and may be discharged over moving parts of the machine for lubricating the same.

The oil eventually is returned to the sump and recirculated. Thus, with a proper setting of the valves 18 and 23, a higher and constant pressure may always be maintained in the passage 17 below the valve 18 than is maintained in the 25 accumulator.

Pressure fluid from the passage 17, which may be said to be at "pump pressure" is employed for holding the pistons of chucks in work stations in the chuck closed position.

The pressure on the pistons in work stations is 30 preferably constant and regulable at will. In the form shown pump pressure acts against the reducing valve 27 and is urged toward the left by means of a spring 28, the stress of which may be adjusted at will by a screw 29.

The rear of the valve 27 is in open communication as shown 35 with the pipe 30 leading, as will be later described, to the tail ends of all cylinders in work stations.

The valve 27, it will be seen, serves to reduce the pump pressure to a degree determined 40 by the adjustment of the spring 28.

Pressure fluid from the accumulator 21 is led by means of a pipe 31 to a control valve casing designated generally 32.

The pipe 31 discharges into a bore 33 in the control valve casing and 45 communicates directly with the central part of the spool valve 34 which controls the clutch piston 35.

It will be seen that the spool valve 34 is 50 slidably within a cylinder and when in the position shown, accumulator pressure fluid is admitted through the passage 36 to the head end of the clutch piston 35 so as to move the clutch

slide 37 toward the right or into the clutched position as shown.

When the spool valve 34 is moved toward the right, pressure fluid from the head end of the piston 35 discharges through the 55 discharge port 38 and accumulator pressure fluid enters the tail end of the cylinder through passage 39 so as to move the piston 35 toward the left to declutch the spindle in loading station

75

Accumulator pressure fluid entering the control valve casing 32 also passes through a branch passage 40 and serves to urge a reducing valve 41 to the right against the stress of the spring 42 regulated as by means of a screw 43. The valve 41, as will be clear, serves to reduce the pressure of the fluid passing from passage 40 to the passage 44. The passage 44, carrying the reduced accumulator pressure, communicates 10 with the central part of a spool valve 45 which may be termed the main control valve of a machine since it is manually or otherwise actuated to control both the clutching and chucking functions.

15 The spool control valve 45 is slidable in a cylinder 46 having the two end exhaust passages 47-48. The cylinder 46 has communicating therewith a pipe 49 leading from near the left-hand end thereof to a bore 50 in a fixed distributor plug 51 carried by the frame of the machine. A second pipe 52 leads from near the right-hand end of the cylinder 46 and communicates with a second bore 53 in the fixed distributor plug 51. The distributor plug, through passages to be described, communicates with and controls the passage of fluid to the ends of the cylinders of the spindles in both the loading and work stations. It may be here noted that the reduced pump pressure pipe 30 communicates with a bore 54 in the 30 distributor plug 51.

As shown in Figs. 1, 2, 2a and 2b, the distributor plug 51 is provided with a short circumferential passage 55, communicating with the bore 50 and consequently with the pipe 49. This short 35 passage 55 communicates through a pipe 56 with the tail end of the cylinder of the spindle in loading station. The distributor plug 51 has a second short circumferential passage 57 communicating with the bore 53 and consequently with the pipe 52. The head end of the cylinder of the spindle in loading station communicates with the passage 57 through a pipe 58. As will be later described, the main control valve 45 serves to alternately connect the ends of the chucking cylinder 40 in loading station with a source of accumulator pressure fluid and with exhaust for actuating the chuck. The distributor plug 51 has a relatively long circumferential passage 59, circumferentially aligned with but out of communication 45 with short passage 55, and communicates with the bore 54 and consequently with the reduced pump pressure pipe 30. The tail end of each of the cylinders of spindles in work stations are connected by means of pipes designated 56' (in 50 all respects the same as pipe 56 in loading station) with the circumferential passage 59. Thus, reduced pump pressure from the pipe 30 is always maintained on the tail ends of the piston of each cylinder in work stations and the chucks in such 55 stations are consequently maintained closed and by a constant but regulable pressure. The distributor plug 51 has still another long circumferential passage 61, circumferentially aligned with but out of communication with short passage 57, 60 and communicates with a bore 62 open to the atmosphere. The head end of each cylinder of each spindle in work stations is connected by means of a pipe 58' (in all respects the same as pipe 58 in loading station) with such long circumferential passage 61 and consequently is open 65 to the atmosphere as long as those pistons are in work stations. Such atmospheric connection is desirable to prevent any pressure fluid leaking past the piston from building up on the head 70 end of the cylinders while in work stations. All 75

of the pipes 56-58 are secured in radial bores in a sleeve manifold 64 which quite closely fits the distributor plug 51 and which rotates with the spindle carrier in its indexing movements. It will be observed that when each chucking cylinder, as 12, is indexed to the loading station, the opposite ends thereof will be connected only with the short passages 55-57 and will have respectively passed out of communication with the long circumferential passages 59-61. Thus, any pressure changes of the chucking cylinder in loading station will in no wise affect the pressure condition in the cylinders of spindles in work stations.

As heretofore indicated the chucking and unchucking is controlled by the spool control valve 45. The latter is moved by means of its piston rod 65, connected to a lever 66 fixed on a shaft 67 journaled in the frame. The shaft 67 also has fixedly secured thereto an actuator, such as a handle 68, so that upon rocking of the handle 68 the spool valve 45 will be moved. When the handle 68 has been moved to the position shown in Fig. 1, the spool valve 45 will be in its extreme left-hand position as determined by the adjusting nuts 69 on the valve stem 65. Pressure fluid from the accumulator pipe 31 will then enter through passages 40-44 and around the spool valve, thence into and through the pipe 49 to bore 50, short annular passage 55, pipe 56, and to the tail end of the cylinder of the spindle in loading station. The piston 11 will then be moved toward the left, as viewed in Fig. 1, so as to cause the chuck to grip the work piece. During such movement of the piston 11 toward the left, oil or other pressure fluid at the head end of the piston 11 will escape through pipe 58, short passage 57, bore 53, pipe 52, thence to the right-hand end of the control cylinder 46 and then through the exhaust passage 42 back to the sump. During such actuation of the chuck, it is to be observed that all of the cylinders of spindles in work stations are constantly subjected to the reduced pump pressure from pipe 30 and are in no wise affected by the chucking and unchucking of the work in the loading station. When the control valve 45 is moved toward the right, as by means of the handle 68 so as to open the pipe 49 to the exhaust pipe 47 and to open the pipe 52 to the central portion of the spool valve 45, pressure fluid through the pipes heretofore described will enter the head end of the cylinder 12 in loading station and fluid from the tail end of such cylinder will escape through the exhaust port 47 of the control cylinder. Thus, movement of the handle 68 in the proper direction serves to shift the spool valve for chucking and unchucking work in the loading station.

The clutching mechanism for the spindle, as heretofore indicated, is also controlled by the handle 68 and main control valve 45. In the form disclosed, and as is more specifically set forth in said Gridley et al. application, each spindle has its own individual clutching fork 70 carried around with the spindle carrier during indexing. Each said fork is provided with a finger 71 which during indexing to the loading station engages within a circumferential groove 73 in a part of the clutch slide organization designated generally 37. The clutch slide 37 is connected as by means of a piston rod 72 with the clutch piston 35 heretofore described. The clutch slide itself may be slidably mounted as shown on a pair of parallel bars 74-74 fixedly carried by the frame. When the clutch spool valve 34 is moved to the position 75

shown in Fig. 1, it will be clear that the clutch piston 35 will be moved toward the right and the spindle clutched to the drive train. Also, as heretofore described, with the main control spool 5 valve 45 in its left-hand position as shown in Fig. 1, the work will also be chucked.

If the work piece were chucked and the spindle put in rotation simultaneously, there would be great danger to the hands of the operator holding the work piece in the chuck. Therefore, we have provided means for causing a substantial time lag between chucking up of a new work piece in the loading station and the clutching of the cylinder to the drive train so as to give the operator ample time to remove his hand after the work piece is securely chucked before the spindle is put in rotation. If we assume the chuck 9 of Fig. 1 to be open the normal operation would be for the operator to put in a new work piece 10 and hold the same in the chuck (which would not be in rotation at that time) and then move the control handle 68 to its full left-hand position, as shown in Fig. 1, thus moving the spool control valve 45 to its extreme left-hand position, 15 as shown in Fig. 1. As heretofore described, the chuck would immediately be closed by accumulator pressure fluid flowing as heretofore fully described. With the spool valve in the extreme left-hand position, pressure fluid from the passage 44 would then flow through a restricted or bleed passage 75 and thence to the right-hand end of a piston 76 which is backed up by a spring 77, the stress of which may be controlled by an adjusting screw 78. The flow of fluid through the 20 restricted passage 75 is relatively slow and builds up slowly in volume behind the piston 76 so as to urge the same toward the left and finally into the position shown in Fig. 1. The piston 76 through its piston rod is connected to a lever 79 pivoted at 80 to the control valve casing and connected at its opposite end to the piston rod of the clutch spool valve 34, as will be clear. When the main control valve 45 is moved to its extreme 25 left-hand position as shown, therefore, the chucking up of the work piece will be very rapid. As soon as the operator feels the work piece is securely chucked, he removes his hand. Thereafter the spindle is not immediately put in rotation because the flow of fluid through the restricted passage 75 is relatively slow and therefore there is a substantial time lag between the chucking up of the work piece and the movement of the clutch spool valve 34 to its left-hand position so as to cause the clutch slide 37 to be moved to the right 30 and the spindle clutched to the drive train. The time lag between chucking up and clutching of the spindle to the drive train may be varied by varying the extreme left-hand position of the control spool valve 45 by means of the adjusting 35 nuts 69 on the control spool valve piston rod 65, since the left-hand flange of the valve 45 when in extreme left-hand position determines the extent of restriction of the passage 75.

When a new work piece has been chucked and 40 the spindle clutched to its drive train, under normal conditions the spindle carrier is indexed so as to bring the new work piece into the first work station and to bring the spindle from the last work station into the loading station. We prefer- 45 ably provide means for automatically declutching the rotating spindle in the loading station from the drive train so that the operator merely unchucks the finished work piece preparatory to inserting a new work blank. The automatic declutching of the spindle is for the most part mere-

ly a time saver and the spindle could be declutched by hand by moving the handle 68. However, in the form shown, wherein we provide means for automatically declutching the spindle when it arrives in loading station, there is a rocking lever 81 pivoted at 82 to a fixed frame bracket 83. This bracket 83 may be conveniently fixed to one of the fixed frame slide bars 74. The lower end of the lever 81 is provided with a cam roll 84 engageable by a cam 85 on the main or other 10 cam shaft 86 of the machine, the positioning of the cam 85 being such that it rocks the lever 81 at about the completion of the indexing movement. The upper end of the lever 81 is pivoted at 87 to a link 88 pivotally connected at its opposite 15 end as at 89 to the lever 63, which, as heretofore stated, is unitarily movable with the hand lever 68. The cam 85 is only high enough to rock the lever 81 a distance sufficient to open the left-hand end of the passage 75 to the exhaust 20 47 (see dotted line position of valve 45 in Fig. 3) but is not sufficient to open the chucking pipe 49 to exhaust nor to open the chucking pipe 52 to the pressure passage 44. As soon as the left-hand end of the passage 75 is freely opened 25 to the exhaust pipe 47, pressure fluid quickly flows from the right-hand end of the piston 76 and, under the influence of the stressed spring 77, the lever 79 is rocked so as to quickly shift the clutch control spool valve 34 to its extreme right-hand 30 position, thus opening the tail end of the piston 35 to accumulator pressure fluid from passage 33 and opening the head end of piston 35 to exhaust port 38. The clutch slide 37 will then be rapidly 35 moved by the piston 35 in its left-hand movement 40 so as to declutch the spindle in loading station from the drive train or gear 8. Movement of the slide 37 toward the left will also bring the flange 90 into engagement with a fixed brake shoe device 91 and continued fluid pressure will cause 45 the frictional engagement between the flange 90 and the brake shoe 91 to quickly stop the rotation of the spindle. The operator then moves the handle 68 from its mid-position, to which it was 50 moved by the cam, to the extreme right-hand position, this movement serving to connect the chucking pipe 49 with exhaust and the unchucking pipe 52 with the pressure passage 44 so as to 55 unchuck the work piece. A new work piece is then inserted and held in the chuck by the operator and the handle 68 then moved to its extreme left-hand position as shown in Fig. 1. As heretofore described, this movement positions the spool valve 45 in its extreme left-hand position and causes immediate chucking of the work piece and, due to the restricted passage 75, a delayed clutching of the spindle to the drive train giving the operator ample time to remove his hand after chucking up a new work piece and before the spindle is clutched to the drive train. Such is 60 the normal operation.

However, we have provided means for preventing the operator from unchucking the finished work piece unless and until the clutch slide has been moved to its extreme left-hand or unclutched 65 position. The safety means employed is best shown in Figs. 1, 3, 6, and 7. The link 88 is provided with an elongated slot 92. The fixed frame bracket 83, which pivotally carries the lever 81, carries a plunger member 93 having a conical nose 94 which, when the clutch sleeve 37 is in its extreme left-hand or declutched position, fits in a registering conical opening 95 in the clutch sleeve, the positioning of the plunger 93 and conical opening 95 being such that they register 70 75

with each other when the clutch slide is in its extreme left-hand or declutched position. However, should the clutch slide for any reason, such as a failure of pressure fluid, breakage of a pipe 5 or the like, fail to be moved to its extreme left-hand or declutched position the conical nose 94 will ride upon the flat portion of the slide 37 and the tail 96 of the plunger 93 will project into the slot 92, as shown in Fig. 7, and positively prevent 10 the operator from moving the control handle 68 to its extreme right-hand or unchucking position. It may be here stated that when the cam 85, through the lever 81, moves the control handle so as to declutch the spindle in loading station, 15 the link is positioned about as shown in Fig. 7, that is, with the left-hand end of the slot about in engagement with the tail 96 of the plunger. In the normal course of events, the clutch slide does move to its extreme left-hand or declutched 20 position and then the plunger 93 is depressed by its spring 97 so as to withdraw the tail 96 from the slot and the operator then unchucks the finished work piece by moving the handle 68 to its extreme right-hand position. The operator is 25 thus protected against injury by reason of the fact that he is unable to unchuck a finished work piece until the spindle has been completely declutched from the drive train. If a heavy finished work piece were discharged from the chuck while 30 in rotation there is likelihood of further damage to the operator, the work piece or the machine. Furthermore, the operator, as heretofore described, is protected from injury caused by a premature clutching of the spindle in loading station after chucking of a new work piece, that is 35 to say, the delay in clutching the spindle is sufficient after the new work piece is chucked to permit the operator to remove his hand from the chucked work piece before clutching takes place. 40 Under normal hand loading conditions the operator has ample time to unclutch the finished work piece and chuck up a new work piece and permit the spindle to be clutched to the drive train during the time that the spindle carrier 45 is at rest and the tools are operating on work pieces in the work stations; that is, the unchucking, chucking and clutching can ordinarily be performed by the operator between indexing movements of the spindle carrier. However, if 50 for some reason the operator fails to move the handle 68 to close the chuck and again put the spindle in rotation, or if through failure of pressure or insufficient pressure of the pressure fluid the work is not chucked and the spindle is not 55 clutched to the drive train, failure of either of which functions might seriously injure tools and other parts of the machine, the machine will be stopped, or at least the feed functions thereof will cease, prior to indexing of a spindle from 60 loading station to the first work station. In the form shown the clutch slide 37 carries a lever 98 pivotally mounted thereon at 99 and urged in a clockwise direction by means of a light spring 100. Thus the lever 98 being pivoted to the movable clutch slide 37 moves bodily with the latter during its reciprocation in clutching and declutching of the spindle in loading station. If 65 for any reason the clutch slide 37 has failed to move to its extreme right-hand or clutched position prior to indexing of the spindle carrier, the slide 37 will of course be positioned somewhat to the left of its extreme right-hand position, as viewed in Figs. 1 and 3, and the lower end 101 of the lever 98 will be positioned so as to be actuated by a cam 102 carried by the cam drum 70 on shaft 86 heretofore described. The cam 102 is timed to actuate the lever 98 just prior to normal indexing movement of the spindle carrier. The upper end of the lever 98 carries a push pin 103 normally urged toward the left by 75 means of a spring 104 and limited in its left-hand movement by a head 105. The nose 106 of the push pin is positioned to engage a push button 107 of an electric switch so as to close a contact and the positioning of the parts is such that unless the clutch slide 37 is in its extreme right-hand position, the cam 102 will rock the lever 98 sufficiently far to cause the push pin 103 to engage the push button 107 and close the contact as aforesaid. Normally it will be observed 15 that with the clutch slide 107 in its extreme right-hand or clutched position, the lever 98 will be bodily moved so far to the right that even if engaged by the cam 102 the nose 106 of the push pin would not be engageable with the push button 107 of the switch. However, when the push button 107 is depressed, the contact is closed and, as shown diagrammatically at the left of Fig. 1, line current through the lines 108 will be caused to pass through the coil 109 of a 20 solenoid, thus sucking up the core 110 and through a link and bell crank lever 111, the lever 112 of the main feed clutch of the machine is thrown out and thus all of the feed works and consequently the indexing movement of the 25 machine is stopped. The feed clutch throw out mechanism may be substantially the same as is disclosed in Montgomery et al. application, Serial No. 689,596, filed September 15, 1933. The feed works will preferably not be automatically 30 thrown in even though the clutch slide should thereafter be moved to its extreme right-hand or clutched position and the contact 107 broken so as to deenergize the solenoid and release the handle 112 controlling the main feed clutch. 35 The latter is preferably manually thrown in after the cause of the failure of the feed clutch to be moved to its extreme clutched position has been remedied. 40

In normal hand loading the speeds and character of the work pieces are often such that the operator has time to unchuck the finished work piece and chuck a new work piece and get the spindle in rotation before the spindle carrier is indexed. In that case the operation of the 45 machine is continuous. However, under certain conditions, the operator may not have sufficient time to unload the chuck and reload the same with a new work blank in the time between indexing movements and this is particularly so 50 when a last operation on the work piece is to be performed in the loading station and before unloading the chuck. In the latter case the cam 85 is moved around on its cam drum to such a position that the lever 81 is actuated to 55 declutch the spindle after the last operation has been performed in loading station and the tools withdrawn, and of course before indexing. As soon as the clutch slide has moved in the declutching direction, thus carrying the lever 60 98 with it, the latter will be so positioned as to be engaged by the throw out cam 102 and to engage switch 107 so that the entire feed works will be thrown out. The feed works will then 65 be out, the clutch of the spindle in loading station will be out (by reason of cam 85) and the operator may then throw the lever 68 to unchuck the work piece and then chuck up a new work piece and clutch the spindle to the drive train, all as heretofore described. Thereafter the main 70 75

feed works clutch handle 112 may be thrown in to again throw in the feed works so that the spindle carrier will index in the usual manner. The latter cycle of operation may be said to 5 be the truly intermittent cycle, that is, where at the completion of each cycle the machine is stopped.

The machine may also be arranged for full 10 automatic operation, that is, the work pieces may be automatically discharged in loading station 15 and a new work piece fed to the chuck from a magazine and chucked up and the spindle put in rotation, etc. The only changes required for full automatic operation with magazine loading 20 is to provide an additional cam 113 engageable with the roll 84 on the lever 81 arranged to position the lever 81 in the position shown in Fig. 1, that is, the position corresponding to the extreme 25 left-hand position of the handle 68 which causes chucking up of the work piece and clutching of the spindle. The cam 85 being properly positioned will declutch the spindle in loading station and a second cam 114 (to be provided for full 30 automatic operation) will unchuck the finished work piece, after which the magazine will feed a new work piece to the chuck and hold the same 35 therein until the cam 113 has again moved the lever 81 to the position shown in Fig. 1 and the new work piece is chucked and the spindle again 40 put in rotation.

In addition to the parts heretofore described, 45 various other devices and features are or may be incorporated in the mechanism of our invention. We have provided means to throw out the feed works in case of a failure of fluid pressure, which failure might occur at such a time in the cycle as to cause serious damage to tools or other parts of the machine and at such time that the 50 automatic mechanisms heretofore described would not be in a position to throw out the feed works. For example, should the pump drive for some reason fail or the discharge pipe of the pump break, the pressure would immediately fail. In the solenoid circuit 109 we provide a pressure 55 switch 115 which is in parallel with the switch 107 and which is normally held open by pump pressure fluid in the pipe line 15 and branch 116. As soon as the pressure drops in the pump discharge line to a point below the setting of the 60 pressure switch 115, the circuit will be closed so as to energize the solenoid to suck up the armature 110 and throw out the main feed clutch, as heretofore described. The switches 107 and 115 are in parallel so as to provide for the same throw 65 out action, no matter which one is closed, to energize the solenoid circuit.

The accumulator 21 as heretofore described 70 furnishes the pressure fluid for both the clutching and chucking functions. However, unless the accumulator 21 is quite large, there is likelihood of a dangerous drop in pressure in the accumulator 21 due to the substantial drain thereon in rapid clutch and chuck actuation, for example as 75 when the machine is wholly automatically operated and magazine fed. We may therefore employ an additional accumulator 117 connected as by means of a pipe 118 with the central portion of the main control spool valve 45 and which is therefore in communication with the cored passage 44 normally fed by the accumulator 21. The 80 accumulator 117 will therefore be charged by the accumulator 21 during such times as there is no drain on the accumulator 21. The maximum pressure to which the accumulator 117 will be charged is determined by the setting of the re-

ducing valve 41. With the two accumulators 117 and 21 it will be seen that the chucking functions will be accomplished by means of pressure fluid from the auxiliary accumulator 117 but augmented where necessary by the accumulator 21. 5 The accumulator 21 is therefore available for quick actuation of the clutching piston, and very rapid chucking and clutching is possible as where the machine is wholly automatically operated. It may be here stated that with insufficient 10 accumulator capacity the fluid may be drained so rapidly that the chucking and clutching functions will be slow and in fact it may be necessary at times to await the recharging of the accumulator before completion of the chucking or clutching 15 functions, or both. However, with the auxiliary accumulator or an accumulator of ample size, chucking and clutching functions will be rapidly performed.

It will be clear that the pressure fluid furnished by the accumulator is dependent upon the air trapped in the top thereof and compressed during charging of the accumulator. After long continued use the air becomes dissipated from the accumulator and with insufficient air the 20 accumulator action is very sluggish and with no air at all of course the entire action would be dependent upon the pump to furnish the normally 25 large volume of fluid for accomplishing the chucking and clutching functions. Therefore, 30 we have provided means for dumping the accumulators and permitting the same to fill with air at such times as the machine is shut down, for example over night, and, if the machine is operated continuously, it should be shut down, say, 35 every twenty-four hours for the purpose of recharging the accumulators with air. The dumping of the accumulators is effected by the pressure control valve 18 in the regulator valve casing and the pressure reducing valve 41 in the 40 control valve casing. In the form shown the pressure retaining valve 18 is provided with a bore 119 having a side outlet so that when the pump 13 is shut down and pressure for that 45 reason fails, the spring 19 will close the valve 18 and put the bore 119 in communication with the accumulator 21. Fluid from the accumulator 21 will therefore flow through the bore 119 and out the discharge pipe 120 controlled by a hand valve 121 which latter during continuous operation is 50 normally open for the reason that the valve 18 is normally in a right-hand position, as shown in Fig. 1, and no substantial amount of fluid leaks past the valve 18. However, during short shut downs, the valve 121 should normally be closed, 55 except at such times as it is desired to dump the accumulator and recharge the same with air. The reducing valve 41 is likewise provided with a bore 122 having a side opening communicating with the pressure passage 44 and having a second side opening communicating with a discharge or 60 a vent passage 123 which normally should be connected to the discharge pipe 120 and controlled by the same hand valve 121 heretofore described. When the pump is shut down, the valve 65 44 will move to its left or-closed position and fluid from the accumulator 117 will be discharged through the bore and vent passage 123 and finally through the valve 121, as will be understood.

Briefly, the general operation is as follows: 70

The pump 13 is started and builds up a pressure in the bore or passage 17. Pressure fluid then passes through the pipe 30 to hold all of the chucks in work stations closed and that pressure is maintained substantially constant by the 75

reducing valve 27 during the entire normal operation of the machine. As the pressure in passage 17 builds up, the pressure retaining valve 18 opens and permits excess fluid over that required to maintain the chucks closed in work stations to flow to and compress the air in the accumulator 24, thus charging the same. When the accumulator is charged, the pressure of the pressure fluid therein is sufficient to move the regulating valve 23 toward the right and the excess fluid flows through the pipe 26 and discharges over parts of the mechanism to be lubricated and is finally returned to the sump. Each time the pressure in the accumulator drops, as it does when fluid is withdrawn therefrom for chucking and clutching purposes, the valve 23 closes so as to prevent the discharge of fluid through the pipe 26 until the accumulator 24 is again charged. As heretofore stated, the valve 121 in normal operation remains open since the bore 119 in the pressure retaining valve is normally sealed. Pressure fluid then flows through pipe 31 and, assuming the handle 68 to be at the extreme right as shown in Fig. 3, the chuck 25 in loading station will be open and the clutch slide 37 will be in its extreme left-hand position wherein the spindle in loading station is declutched from the power train. A work piece is then inserted in the chuck in loading station 30 and held therein. The hand lever 68 is then moved with one movement to its extreme left-hand position as shown in Fig. 1 thus moving control spool valve 45 to its extreme left-hand position. Pressure fluid from the accumulator 35 24 or the auxiliary accumulator 111, when employed, then flows through pipe 49 to the tail end of the chucking piston 11 in loading station. Fluid from the head end of the chucking piston 11 discharges through pipe 52 and discharge port 40 49 of the control valve cylinder. The work piece is thus rapidly chucked. At the same time, pressure fluid is passing relatively slowly through the restricted passage 75 to the head end of the actuating piston 76 for the clutch control valve. 45 The piston 76 is moved slowly toward the left and in turn moves the clutch spool valve 34 to its extreme left-hand position, as shown in Fig. 1, and at that time pressure fluid from the accumulator 24 passes to the head end of the clutching 50 piston 35 and thus moves the clutch slide to its extreme right-hand position, causing the clutch parts 6-7 to engage and put the spindle in rotation. The feed clutch 112 may then be thrown in and in due course the spindle carrier is indexed to bring the newly chucked work piece into the first work station and, during normal continuous operation, to bring a finished work piece into the loading station. The cam 85 being synchronized with the indexing mechanism then 55 rocks the lever 81 to move the control handle and with it the spool control valve 45 toward the right into an intermediate position sufficient to open the passage 75 freely to the exhaust pipe 47 of the spool control valve casing, and the spring 11 then 60 quickly moves the piston 76 to the right and the clutch spool valve 34 is quickly moved toward the right so as to cause pressure fluid from the accumulator 24 to impinge upon the tail end of the clutching piston 35 and quickly declutch the 65 spindle from the drive train and by reason of the engagement of the flange 99 with the fixed abutment 91 to cause the spindle to stop rotating. The operator then moves the handle 68 to its extreme right-hand position to unchuck the finished work piece. Under normal conditions the

operator is able to so move the handle. However, if for any reason the clutch slide 37 is not in its extreme left or declutched position, the tail 96 of plunger 93 will be projected into the elongated slot 92 and the link 88 and consequently the control handle 68 will be effectively blocked against right-hand movement. However, under normal conditions, the clutch slide 37 will be in its extreme left-hand or declutched position and when the handle 68 is thrown to its extreme right-hand position, namely into the position shown in Fig. 3, the spool control valve 45 will be moved to its extreme right-hand position and the chucking piston 11 will be moved toward the right as heretofore described and the finished work piece unchucked. A new work piece is then inserted and the above noted actions repeated.

Normally the operator may unchuck the finished work piece and chuck up a new one in the time when the spindle carrier is at rest, that is, between indexing movements. However, should it be desired to perform a tooling operation on the work piece after it reaches the loading station, the cam 85 is moved around on its cam drum to such position that it will not declutch the spindle from the drive train until the tooling operation in loading station has been performed, at which time the repositioned cam 85 will rock the lever 81 and declutch the spindle. With the spindle declutched the clutch slide 37 will be in its extreme left-hand position and before indexing the cam 102 will engage the end 101 of the lever 98 so as to rock the same and close the switch contact 107 so as to throw out the feed works. The operator then moves the handle 68 to its extreme right-hand position to unchuck the finished work piece, after which a new work piece is inserted and the handle 68 moved to the extreme left as shown in Fig. 1 to chuck the new work blank and put the spindle in rotation. The main feed clutch handle 112 is then moved manually to throw in the feed works and, in due course, the spindle carrier is indexed and the same operations are again performed. When the machine is to be operated entirely automatically, that is, when the work pieces are fed to the machine from a magazine, the chucking and clutching functions are performed automatically. In that case in addition to the cam 85 for declutching the spindle in the loading station, we provide an additional cam 114 for moving the handle 68 or its equivalent to the extreme right to unclutch the work piece, after which the magazine feeds a new work piece to the chuck and an additional cam 113 then engaging with the roll 84 rocks the lever 81 to chuck the new work piece and put the spindle in rotation. The spindle carrier is then indexed and the same cycle repeated.

It will be seen that we have provided fluid pressure chucking and clutching means which may be actuated at regulable and consequently optimum pressures. Such mechanism may be operated manually, semi-automatically, or fully automatically. Various safety devices have been provided for insuring the safety of the operator, as well as for preventing damage to the machine, tools or work piece due to accidental improper functioning of one or more of the elements of our improved mechanism.

While the invention has been described in considerable detail and as applied to a multiple spindle chucking machine, it is to be understood that the invention may be variously embodied in other types of machines and that the invention may be

used in conjunction with or in lieu of other mechanisms all relating to machines of the character indicated. Various changes, additions and omissions may be made, all within the scope of the 5 invention as defined in the appended claims.

We claim:

1. In a machine of the character indicated, a rotatable spindle, a clutch therefor, fluid pressure actuated means for actuating said clutch for 10 clutching said spindle to a drive member, a chuck carried by said spindle, fluid pressure actuated means for operating said chuck, a valve member for controlling the flow of pressure fluid to and from both of said fluid pressure actuated means, 15 and fluid pressure passage control means for causing one of said fluid pressure actuated means to act in advance of the other.

2. In a machine of the character indicated, a rotatable spindle, a clutch for clutching said 20 spindle to a drive member, fluid pressure actuated means for actuating said clutch, a chuck on said spindle, fluid pressure actuated means for actuating said chuck, a control valve means for controlling the flow of pressure fluid for said fluid 25 pressure actuated means, and positive means for preventing the actuation of one of said fluid pressure actuated means until the other of said fluid pressure actuated means has actuated its actuated member.

3. In a machine of the character indicated, a 30 rotatable spindle, fluid pressure actuated means for controlling a clutch for said spindle, a chuck carried by said spindle, fluid pressure actuated means for actuating said chuck, a control valve 35 for controlling the flow of pressure fluid for said fluid pressure actuated means, a handle for actuating said control valve, and stop means controlled by the position of one of said fluid pressure actuated means for preventing the actuation 40 of said handle to actuate one of said fluid pressure actuated means until the other has acted.

4. In a machine of the character indicated, a 45 rotatable spindle, fluid pressure actuated means for clutching and unclutching the same, a chuck, fluid pressure actuated means for actuating the latter, control means including a manually operable member for sequentially controlling the operation of said fluid pressure actuated means, and detent means controlled by the position of one of said fluid pressure actuated means for preventing full actuation of said manually operable member until one of said fluid pressure actuated means has been moved a predetermined distance.

5. In a machine of the character indicated, a 55 rotatable spindle, fluid pressure actuated means for controlling clutching means for said spindle, a chuck, fluid pressure actuated means for actuating said chuck, a clutching slide, a control valve for both of said fluid pressure actuated means, 60 said valve being movable in one direction to one position for actuating one of said fluid pressure actuated means and movable in the same direction to a second position for causing the actuation of the other of said fluid pressure actuated means, and detent means for preventing movement of said control valve in said same direction to said second position until the first fluid pressure actuated means has been actuated.

6. In a machine of the character indicated, a 70 rotatable spindle, fluid pressure actuated means for controlling clutching means for said spindle, a chuck on said spindle, fluid pressure actuated means for actuating said chuck, a valve for controlling the flow of fluid pressure to both of said fluid pressure actuated means, said valve being

movable to one position to cause a flow of fluid pressure to said fluid pressure actuated means for closing said chuck and for controlling the flow of fluid pressure to said pressure actuated means for clutching said spindle to a drive member, and 5 means for causing a delayed action in the operation of said clutching means in the clutching direction.

7. In a machine of the character indicated, a 10 rotatable spindle, fluid pressure actuated means for controlling clutching means for said spindle, a chuck, fluid pressure actuated means for actuating said chuck, a valve for controlling the flow of fluid pressure to both of said fluid pressure actuated means, said valve being movable to one 15 position to control the flow of fluid pressure for causing said fluid pressure actuating means to unclutch said spindle from its drive means and further movable in the same direction to a second position to control a flow of fluid pressure to actuate said fluid pressure actuated means for unclutching said chuck, and means for preventing said second movement of said valve until said spindle has been completely uncluched from its 20 drive means.

8. In a machine of the character indicated, an indexable spindle carrier, a plurality of rotatable spindles carried thereby, a chuck carried by each of said spindles, fluid pressure actuated means carried by each said spindle for actuating said 30 chucks, clutch means for each said spindle when in loading station, fluid pressure actuated means for actuating said clutch means, and means for providing fluid at independently regulable pressures to actuate said chuck in loading position 35 and for holding said chuck closed when in work station and for actuating said clutching means.

9. In a machine of the character indicated, a 40 rotatable spindle, clutching means therefor, fluid pressure actuated means for controlling said clutching means, a chuck carried by said spindle, fluid pressure actuated means for actuating said chuck, and pressure fluid at independently regulable pressures for actuating said clutching means and for actuating said chuck.

10. In a machine of the character indicated, a 45 rotatable spindle, clutching means therefor, fluid pressure actuated means for actuating said clutching means, a chuck, fluid pressure actuated means for actuating said chuck, means for controlling the flow of fluid pressure to cause said chuck to be actuated to grip a work piece and to cause said clutch to be actuated to clutch said spindle to its drive means, drive means for said 50 machine, and means for stopping said machine upon a failure of either of said fluid pressure actuated means to complete its function.

11. In a machine of the character indicated, a 55 rotatable spindle, a clutch therefor, fluid pressure actuated means for actuating said clutch, a chuck for said spindle, fluid pressure actuated means for actuating said chuck, a single valve for controlling the flow of pressure fluid to both of said fluid pressure actuated means, detent means controlled by the position of said clutch for preventing movement of said single valve to one 60 position until said clutch is completely disengaged.

12. In a machine of the character indicated, a 65 rotatable spindle, a clutch therefor, means for actuating said clutch, a chuck on said spindle, fluid 70 pressure actuated means for actuating said chuck, a valve for controlling the flow of pressure fluid for actuating said chuck, and detent means controlled by the position of said clutch for preventing a flow of pressure fluid to said 75

chuck fluid pressure actuating means to prevent opening of said chuck until said clutch is completely disengaged.

13. In a machine of the character indicated, 5 a rotatable spindle, a clutch therefor, fluid pressure actuated means for actuating said clutch, a chuck carried by said spindle, fluid pressure actuated means for actuating said chuck, a valve movable to one position for controlling the flow 10 of pressure fluid to the fluid pressure actuated means for actuating said clutch to disengage the same, and detent means controlled by the position of said clutch for preventing movement of said valve to permit opening of said chuck until 15 said clutch has been completely disengaged.

14. In a machine of the character indicated, 20 a rotatable spindle, a clutch therefor, a fluid pressure actuated piston for actuating said clutch, an auxiliary control valve for controlling the flow of pressure fluid for actuating said piston 25 and clutch, a chuck on said spindle, fluid pressure actuated means for actuating said chuck, a main control valve for controlling the flow of pressure fluid to said chuck for closing the same, and means actuated by the pressure of pressure fluid flowing to said chuck actuating means for closing the same to actuate said auxiliary valve for controlling said clutch.

15. In a machine of the character indicated, 30 a rotatable spindle, a clutch therefor, a fluid pressure actuated piston for actuating said clutch, an auxiliary control valve for controlling the flow of fluid pressure to opposite sides of said piston for moving said clutch to engaged and disengaged position, a chuck carried by said spindle, fluid pressure actuated means for actuating said chuck, means including a fluid pressure actuated piston for moving said auxiliary control valve, and a main control valve for controlling 35 the flow of fluid pressure to said fluid pressure actuated piston and for controlling the flow of fluid pressure to said fluid pressure actuated means for actuating said chuck.

16. In a machine of the character indicated, 40 a rotatable spindle, a clutch therefor, fluid pressure actuated means for actuating said clutch, a chuck on said spindle, fluid pressure actuated means for actuating said chuck, a single control valve for controlling the flow of fluid pressure to 45 both said fluid pressure actuated means for actuating the same, said control valve being movable to a first position to cause a flow of fluid pressure to said clutch fluid pressure actuating means for disengaging said clutch, means for automatically moving said valve to said first position, and detent means for preventing a further movement of said control valve until said clutch has been 50 disengaged.

17. In a machine of the character indicated, 55 a rotatable spindle, a clutch therefor, fluid pressure actuated means for actuating said clutch, a chuck carried by said spindle, fluid pressure actuated means for actuating said chuck, a main machine feed clutch, means for controlling the flow of pressure fluid to said fluid pressure actuated means, and means for automatically throwing said main machine feed clutch upon a failure of said fluid pressure actuated means to 60 engage said spindle clutch and close said chuck.

18. In a machine of the character indicated, 65 an indexable spindle carrier, a plurality of rotatable spindles carried thereby, a spindle clutch for each spindle, fluid pressure actuated means for actuating each said spindle clutch in loading sta-

tion, a chuck carried by each said spindle, fluid pressure actuated means for actuating each said chuck in loading station, means for controlling the flow of pressure fluid to said fluid pressure actuated means for actuating said chuck and said spindle clutch, a main feed clutch for said machine, and means for automatically disengaging said main feed clutch upon a failure of said fluid pressure actuated means to complete the clutching and chucking functions prior to 10 indexing of said spindle carrier.

19. In a machine of the character indicated, 15 an indexable spindle carrier, a plurality of rotatable spindles carried thereby, a spindle clutch for each said spindle, fluid pressure actuated means for actuating each said spindle clutch in loading station, a chuck carried by each said spindle, fluid pressure actuated means for actuating each said chuck in loading station, control means for said fluid pressure actuated means, and means for automatically actuating said control means to disengage each said clutch automatically in loading station, and manual means for actuating said control means to open each said chuck in loading station.

20. In a machine of the character indicated, 20 an indexable spindle carrier, a plurality of rotatable spindles carried thereby, a spindle clutch for each said spindle, a fluid pressure actuated means for actuating each said spindle clutch in loading station, a chuck carried by each said spindle, fluid pressure actuating means for actuating each said chuck in loading station, and means for automatically preventing a completion 25 of the indexing movement of said spindle carrier until said chuck from loading station has been closed and the clutch of said spindle from loading station engaged.

21. In a machine of the character indicated, 30 a rotatable spindle, a spindle clutch therefor, fluid pressure actuated means for actuating said spindle clutch, a chuck carried by said spindle, fluid pressure actuated means for actuating said chuck, means including a handle for causing said fluid pressure actuated means to disengage said clutch and open said chuck, and detent means controlled by the position of said spindle clutch for preventing movement of said handle to cause an opening of said chuck until said spindle clutch has been disengaged.

22. In a machine of the character indicated, 35 a rotatable spindle, a spindle clutch therefor, fluid pressure actuated means for actuating said spindle clutch, a chuck carried by said spindle, fluid pressure actuated means for actuating said chuck, means including fluid pressure actuated piston for controlling the flow of fluid pressure to said clutch fluid pressure actuating means and a control valve for controlling the flow of fluid pressure to said piston and to said 40 chuck fluid pressure actuating means, and a restriction to restrict the flow of pressure fluid to said piston whereby the latter is moved slowly so as to prevent actuation of said spindle clutch to clutched position until said chuck has been closed.

23. In a machine of the character indicated, 45 an indexable spindle carrier, a plurality of chucks carried thereby, means for actuating each said chuck in loading station, and means for stopping said machine upon a failure of each chuck to 50 close before or when indexed to the first work station.

24. In a machine of the character indicated, 55 an indexable spindle carrier, a plurality of rotatable spindles carried thereby, a spindle clutch for 60

each said spindle, a chuck for each said spindle, means for actuating said chucks in loading station, means for actuating each said clutch in loading station, and means for stopping the machine 5 upon a failure of a clutch to be engaged before or when indexed to the first work station.

25. In a machine of the character indicated, a rotatable spindle, a clutch therefor, a chuck carried by said spindle, means for actuating said 10 clutch and chuck, and means controlled by the condition of said clutch for preventing opening of said chuck until said clutch has been disengaged.

26. In a machine of the character indicated, a 15 rotatable spindle, a spindle clutch therefor, fluid pressure actuated means for actuating said spindle clutch, a chuck carried by said spindle,

fluid pressure actuated means for actuating said chuck, means for controlling said fluid pressure actuated means to cause the latter to actuate said clutch and chuck, and means controlled by the position of one of said two last mentioned 5 members for controlling the actuation of the other of said members for the purpose described.

27. In a machine of the character indicated, a rotatable spindle, a clutch therefor, a chuck carried by said spindle, means for actuating said 10 clutch and chuck, and means for preventing the actuation of one of said two last mentioned members until the other of said members has been actuated.
